US0D1094420S

(12) **United States Design Patent** (10) **Patent No.:** **US D1,094,420 S**
(45) **Date of Patent:** **** Sep. 23, 2025**

(54) **DISPLAY SCREEN OR PORTION THEREOF WITH GRAPHICAL USER INTERFACE**

(71) Applicant: **Apple Inc.**, Cupertino, CA (US)

(72) Inventors: **Lyam Joseph Bewry**, San Francisco, CA (US); **Andrew Patrick Clymer**, San Jose, CA (US); **Alan C. Dye**, San Francisco, CA (US); **Thalia Jimena Echevarria Fiol**, Cupertino, CA (US); **Dylan Ross Edwards**, San Jose, CA (US); **Robert W. Hanley**, Walnut Creek, CA (US); **Bobby Martin, Jr.**, Palo Alto, CA (US); **Eric Lance Wilson**, San Jose, CA (US)

(73) Assignee: **Apple Inc.**, Cupertino, CA (US)

(**) Term: **15 Years**

(21) Appl. No.: **29/946,551**

(22) Filed: **Jun. 10, 2024**

(51) LOC (15) Cl. **14-04**

(52) U.S. Cl.

USPC **D14/487**

(57) **CLAIM**

The ornamental design for a display screen or portion thereof with graphical user interface as shown and described.

DESCRIPTION

The sole FIGURE is a front view of a display screen or portion thereof with graphical user interface showing the claimed design.

The peripheral dashed broken lines depict a display screen or portion thereof, and form no part of the claimed design. The dashed broken lines depict portions of the graphical user interface which form no part of the claimed design.

1 Claim, 1 Drawing Sheet
